FRAME FOR AN OVERSTUFFED SOFA OR THE LIKE

Henry Klein, 252-05 Culman Ave.,
Little Neck, N.Y. 11362

Filed July 23, 1968, Ser. No. 12,860

Term of patent 7 years

Int. Cl. D6—01

U.S. Cl. D15—11

FIG. 1

FIG. 2

FIG. 3

FIG. 5

FIG. 4

FIG. 1 is a top plan view of a frame for an overstuffed sofa or the like;

FIG. 2 is a front elevational view of the frame;

FIG. 3 is a rear elevational view of the frame;

FIG. 4 is a side elevational view of the frame; and

FIG. 5 is a side elevational view of the frame.

The essential features of the frame reside in those portions shown in full lines on the drawing.

I claim:

The ornamental design for a frame for an overstuffed sofa or the like, substantially as shown and described.
